HEAT EXCHANGE APPARATUS

Felipe Munilla Durán, Washington, D. C.

Application May 27, 1935, Serial No. 23,761

11 Claims. (Cl. 257—244)

This invention relates to heat exchange apparatus and more particularly to a novel form of apparatus employing a rotary impeller for handling all gaseous fluids in heat exchange relation in a more efficient manner than heretofore accomplished.

One object of the invention is to provide a novel form of apparatus which shall employ a hollow rotary impeller adapted to be driven by 10 a motive heating fluid and receive therein a fluid to be heated by said fluid.

Another object of the invention is to provide a heat exchange apparatus of the character designated in which air shall be forced through 15 said impeller in heat exchange relation to the motive heating fluid which drives said impeller.

Another object of the invention is to provide an apparatus of the character designated having a novel form of impeller structure which shall be 20 more efficient than similar apparatus heretofore employed.

Another object of the invention is to provide a novel form of heat exchange apparatus which shall be particularly adapted for use with the 25 exhaust of a prime mover such as a turbine, steam engine, or internal combustion engine.

Another object of the invention is to provide a heat exchanger of the character designated in which a portion of the motive heating fluid shall 30 also be utilized to effect a novel circulation of the medium to be heated in the apparatus.

A further object of the invention is to provide apparatus of the character designated which shall be durable in construction, simple in operation 35 and readily applied to a wide variety of uses.

These and other objects of the invention will be more manifest from the following specification and drawings and particularly set forth in the claims.

40 In the drawings:

Figure 1 is a vertical sectional view of a heat exchanger embodying the features of my invention;

Figure 2 is a horizontal sectional view on line 45 2—2 of Fig. 1;

Figure 3 is a view in elevation of a heat exchanger assembly and connections therefor; and

Figure 4 is a sectional view on line 4—4 of Fig. 3.

50 Referring to the drawings, there is shown in Figs. 1 and 2, a novel heat exchanger unit constructed and arranged in accordance with my invention. A heat exchange unit of this kind is particularly desirable and adaptable for utilizing the heat of such fluids as exhaust steam, or

hot gases from the exhaust of an internal combustion engine. The heat from such sources which is usually wasted may be put to useful work by heating air for use in various types of heaters. For example, when applied to vehicles such as automobiles, motor boats and railway cars, the hot air may be utilized to heat a compartment or it may be directed against the windows thereof to prevent the collection of moisture thereon, or it may be used for any other purpose for which 10 fresh heated air may be desired.

The apparatus shown in Figure 1 consists of a stationary casing unit 10 which may be supported in the exhaust line of an internal combustion engine indicated by the numeral 11. The outside 15 part of the casing may be made of light sheet metal and protected by heat insulation material such as asbestos, or it may be made of any other suitable heat insulation material to adequately conserve the heat of the motive fluid employed 20 in the heat exchanger. Enclosed in the casing 10 is a hollow rotary impeller 10' mounted in suitable bearings 12 and 13 which shall reduce friction to a minimum and thus enable the impeller to be rotated at high speed by the impinging action of the motive fluid on the impeller. This motive fluid is delivered from the conduit 11 by a nozzle 14 which directs it against suitable inclined vanes 15 located on the outer periphery of the impeller indicated by the numeral 16.

The impeller 10' is preferably made of sheet metal, such as aluminum, having high heat conducting properties so as to facilitate the transfer of heat from the motive heating fluid to the 35 air flowing through the interior of the impeller in heat exchange relation to the outside gaseous heating medium. The impeller consists of a top wall 17 and an inner top wall 18 spaced therefrom to provide an annular outlet passage 19 as 40 hereinafter described. Depending from the wall 18 is a plurality of spaced annular walls 20, 21, 22, 23 and connecting curved portions to form with complementary pairs of spaced walls 24—25, 26—27, 28—29, and end wall 16, a sinuous passage 45 leading from an axial or central inlet passage 30 to the periphery and thence to the discharge conduit or passage 19 as indicated by the arrows. It will be noted that the interior arrangement of the passages provides for bringing 50 the heated air into contact with the periphery of the impeller and to further facilitate the transfer of heat at this region, the surface 16 is corrugated to increase the heat transfer surface. These corrugations are directed diagonally of the 55

surface 16 so as to further aid in facilitating the handling of air.

To further facilitate the travel of air through the impeller, the depths of the annular walls 5 forming the sinuous passage vary from the center to the periphery so that the air may undergo a velocity pressure conversion in the passages. To further aid in increasing the efficiency of the apparatus in handling and delivering heated air, 10 the outer annular passages are provided with a plurality of inclined vanes 31—32 located in adjacent passages. It will be noted that the vanes in adjacent passages are oppositely inclined in order to force the air into the adjacent hotter zone 15 or passage and finally discharge the same at the outlet in the desired highly heated condition, and under a pressure sufficient to deliver it to any convenient apparatus for use.

The heating gases delivered to the casing are 20 circulated around and through the bottom of the impeller by a series of concentric deflector plates 33—33 mounted on the bottom of the casing 10 and arranged to deflect the gases between annular walls 24—25 for example. Further circulation 25 of a portion of the gases to draw the same from the casing and force the same to an external point of application is accomplished by a plurality of angularly disposed blades or vanes 34—34 located on the exterior top portion 30 of the impeller.

Outside air to be heated is supplied to the central inlet 30 by an outside propeller 35 including a plurality of funnel shaped conduit arms 36 adapted to collect air and force the same into 35 the interior of the impeller 10'. The outside propeller arms 36 are commensurate in extension radially, with the inside impeller 10' thereby balancing the rotative parts.

Heated air is discharged from the rotary impeller 40 through the top conduit 19 thereof by an axial outlet member 37 which is arranged to form a seal with a stationary delivery tube 38. This tube 38 connects with any point of application to which the heated air may be directed such 45 as a register 39 for a compartment or body of a motor vehicle, as shown in Fig. 3. To further improve the heat efficiency of my improved apparatus, the conduit 38 is enclosed by an outer conduit 40 which connects directly with the top 50 of the casing 10 by conduits 41 and 42 adjacent to the vanes 34—34. The return of the gases from the conduit 40 is effected by a conduit 42' located between the annular walls of the conduits 38 and 40, Fig. 4. The conduit 42' connects with 55 the casing discharge outlet conduit 11' by a conduit 43. Hot gas passes from the casing 10 through the conduits 41 and 42 into conduit 40 and returns through conduits 42' and 43 to the outlet 11'.

Having thus described apparatus constructed and arranged in accordance with my invention, the operation thereof is carried out in the following manner: Exhaust gases from a fluid pressure motor such as an internal combustion engine 65 and the like are utilized to heat air for any desired purpose in order to conserve the heat of such gases which would ordinarily be wasted. The hollow impeller is rotated by the pressure of the gas delivered from the nozzle 14 and the rotation 70 of the outside propellers 36—36 draws fresh air inwardly and delivers it to the passages on the interior of the impeller 10' where it is heated by the highly heated gases from the exhaust. The air is heated in passing through the impeller 75 and is delivered from the region of the periphery

of the impeller where it is in thermal contact with the hottest gas.

To further aid in the efficiency of the heat exchange system, a portion of the heating gases is circulated in an exterior conduit 40 surrounding the air outlet. This circulation is accomplished by supplementary vanes 34—34 on the top of the impeller. These vanes are inclined to draw gas from the peripheral portion of the casing 10 and direct it through the external 10 conduit 40.

Having thus described a heat exchange apparatus embodying a preferred construction, it is obvious that various changes may be made there-in without departing from the scope of the invention as defined in the appended claims. For example, an air cleaner as indicated by the strainer member 44, may be located at the entrance of the intake conduit, or else where in the apparatus as may be desirable. Furthermore, the arms 36 may be dispensed with and a single funnel shaped member provided in its place and the structure balanced accordingly.

What I claim is:—

1. In a heat exchange device, the combination 25 of a casing, a nozzle for admitting a heated fluid to said casing, a hollow rotary impeller mounted in said casing and rotated by the fluid from said nozzle, a central passage for admitting air to the interior of said impeller, a plurality of annular 30 passages formed by the interior walls of said impeller to provide a sinuous passage radially of the impeller from the central passage to the periphery thereof, and means for conducting the heated air from the peripheral portion of the 35 impeller.

2. Apparatus of the character designated in claim 1 including means located exteriorly of the casing and connected to the impeller for forcing air through the central passage. 40

3. Apparatus of the character designated in claim 1 including a funnel shaped inlet member located exteriorly of the casing and carried by the impeller for directing air into the central 45 passage.

4. Apparatus of the character designated in claim 1 in which certain of the adjacent annular passage walls are provided with oppositely inclined vanes whereby the movement of air is accelerated through the impeller. 50

5. Apparatus of the character designated in claim 1 including vanes on the outer periphery of the impeller for receiving motive fluid from the nozzle, and other deflector vanes on the bottom of the casing for directing hot gases against 55 the walls of the annular passages.

6. Apparatus of the character designated in claim 1 including a centrally disposed outlet formed by the impeller walls and communicating directly with the peripheral inner portion of the 60 impeller.

7. Apparatus of the character designated in claim 1 including a centrally disposed outlet communicating directly with the peripheral inner portion of the impeller, and a conduit surrounding the outlet and communicating directly with the interior of the casing for conducting a portion of the heating fluid from the casing in heat exchange relation to said outlet. 65

8. Apparatus of the character designated in claim 1 in which the walls forming the sinuous passage progressively vary in depth from the central passage to the peripheral portion of the impeller. 70

9. Apparatus of the character designated in 75

claim 1 in which the outer peripheral wall of the impeller is provided with a corrugated surface, a plurality of angularly disposed vanes mounted on said surface, and other vanes on the impeller arranged to discharge a portion of the hot gases from the casing.

10. Apparatus of the character designated in claim 1 having an axial outlet conduit for hot air from the impeller, a conduit communicating with 10 the interior of the casing and surrounding the air discharge conduit, and means for creating a circulation of gases in the exterior conduit.

11. In a heat exchange device, the combination of a casing, a nozzle for admitting a heated fluid to said casing, a hollow rotary impeller mounted in said casing and rotated by the fluid from said nozzle, a central passage for admitting air to the interior of said impeller, and means for conducting the heated air from the peripheral portion of the impeller. 5

FELIPE MUNILLA DURÁN. 10
